UNITED STATES PATENT OFFICE.

THOMAS WILTON HAND, OF SHEFFIELD, ENGLAND, ASSIGNOR TO DAVY BROTHERS LIMITED, OF SHEFFIELD, ENGLAND.

STEAM HYDRAULIC INTENSIFIER.

1,323,590.

Specification of Letters Patent.

Patented Dec. 2, 1919.

Application filed January 19, 1918. Serial No. 212,550.

To all whom it may concern:

Be it known that I, THOMAS WILTON HAND, a subject of the King of Great Britain, and resident of Park Iron Works, 5 Sheffield, in the county of York, England, have invented certain new and useful Improvements in Steam Hydraulic Intensifiers, of which the following is a specification.

This invention relates to steam hydraulic 10 intensifiers of what may be termed the "improved inverted" type described in the specification of the application for Letters Patent filed Aug. 20, 1917, Serial No. 187,271, according to which the steam cylinder of 15 the intensifier is mounted above and in axial alignment with the hydraulic cylinder while the movable member, whether ram or cylinder, of the hydraulic portion of the intensifier is placed lowest and is connected with 20 the steam piston by means of side rods.

By the present invention improved mechanism is provided for controlling the valve or valves whereby steam is admitted and exhausted to and from the steam cylinder 25 of the intensifier and also to and from the lifting cylinders of the hydraulic press (*e. g.*, forging press, shears or the like) which is worked by the intensifier, the control of the steam valve or valves of the intensifier 30 being effected conjointly by a handing-lever and by hunting-gear actuated by the steam piston of the intensifier in such manner that the movement of said piston in performing its working stroke automatically causes 35 the supply of steam to be cut off in accordance with the position in which the handing-lever is held; while trip mechanism is interposed between the same handing-lever and the steam valve or valves appertaining 40 to the lifting cylinders for the purpose of automatically coupling and uncoupling said lifting cylinder valve or valves to and from the handing-lever in such manner that steam is normally admitted to the lifting cylinders 45 (so as to tend to raise the main press-head) but is exhausted therefrom during the earlier part of the pressing strokes of the main hydraulic ram of the press when the latter is being worked with long strokes.

Hunting-gear employed for a similar purpose in what may be termed a non-inverted intensifier has heretofore comprised a floating lever coupled to the handing-lever, to the valve or (with the necessary lost mo-

tion) to the valves of the intensifier steam cylinder, and a leverage-system connected with an inclined, movable, counterweighted control-bar which bears against a roller moving as one with the steam piston of the intensifier; the initial inclination of this control bar being determined by the angular position to which the handing-lever is set for each stroke of the press, so that the supply of steam to the steam cylinder of the intensifier is cut off automatically at an 60 earlier or a later point in the stroke of the steam piston in accordance with such position of the handing-lever.

According to the present invention an inclined or tapering cam-bar is fixed by its 70 lower end to the lower end of the movable member whether ram or cylinder, of the hydraulic portion of the intensifier so as to move lengthwise as one therewith, and is offset from said member so as to be adapted to bear against one arm of a counterweighted lever having a stationary fulcrum; said lever being coupled to the handing-lever, and also to the trip-mechanism for operating the steam valve or valves of the lifting 80 cylinders of the press, through the medium of a floating-lever which itself is coupled to the valve or (with the necessary lost motion) to the valves of the intensifier steam cylinder; the point in the stroke of the steam piston whereat the supply of steam is cut off being thus determined by the setting of the hand-lever.

In the accompanying drawings, Figure 1 is a side elevation showing an example of 90 an intensifier of the "improved inverted" type above referred to, to which the present invention is applied; Fig. 2 is a similar view as seen from the right hand side of Fig. 1; Fig. 3 is a plan view, partly in 95 section through the stool which supports the steam and hydraulic cylinders of the intensifier, and with various parts omitted; Fig. 4 is a top plan view; Fig. 5 is a partial view similar to Fig. 1, but drawn to a larger 100 scale, and showing the steam valves in section; Fig. 6 is a sectional elevation of the trip mechanism for controlling the actuation of the lifting-cylinder steam valve, drawn to a still larger scale; Fig. 7 is a 105 sectional elevation of a preferred form of the hydraulic "working-valve" which controls the connection between the hydraulic

main pressure pipe and the usual air-vessel; and Fig. 8 is an outside elevation of the same valve, viewed as in Fig. 1.

In the example illustrated, the steam cylinder 11 of the intensifier is mounted upon a stool 12 which rests upon the foundation 13, and the stationary member of the hydraulic portion of the intensifier is the hydraulic cylinder 14 which is supported by the stool 12 so as to extend beneath and in axial alignment with the steam cylinder 11; while the hydraulic ram 15, which is fitted to work through a stuffing box 16 at the open lower end of the cylinder 14, carries at its lower extremity a crosshead 17 whereby the ram 15 is coupled to the piston (not shown) within the steam cylinder 11 through the medium of a pair of side rods 18, 18 which extend parallel with and on opposite sides of the common axis of the cylinders 11 and 14 and ram 15, the rods 18, 18 passing through stuffing boxes (not shown) in the bottom cover of the steam cylinder 11, and through guides 19, 19 in the stool 12 (see Fig. 3). The hydraulic main or high-pressure pipe leads from an outlet 20 near the lower end of the hydraulic cylinder 14 to the main hydraulic cylinder (not shown) of the hydraulic press (e. g. forging press, shears or the like) worked by the intensifier; this high-pressure pipe being in two sections, whereof the one section 21 extends from the cylinder 14 to the hydraulic working-valve 22 which controls communication between the hydraulic high-pressure pipe and the hydraulic low-pressure pipe 23 connected with the usual air vessel (not shown), while the other section 24 leads underground from the working-valve 22 to the main hydraulic cylinder of the press.

The cam-bar by means of which, according to the present invention, the steam valves of the intensifier are controlled as already stated, consists of an upright, upwardly-tapering bar 25 fixed by its lower end 26 to the crosshead 17 so as to move vertically as one with the ram 15 and steam piston of the intensifier. One edge 27 of the bar 25 extends parallel with the direction in which the bar moves, and is guided by sliding in contact with a grooved stationary roller 28 carried by a bracket 29 which is fixed to the cylinder 14 near the lower end of the latter, while a grooved roller 30 carried by a lever, which may be termed the main lever (of the valve-gear) bears constantly against the opposite or inclined edge 31 of the bar 25 so as to be moved in one direction or the other as said bar travels upward or downward; a short portion 31^a of the lower end of the edge 31 being formed with a steeper slope (see Fig. 1) so as to be adapted to cause the exhaust valve of the intensifier steam cylinder to open rapidly when the steam piston closely approaches

the upper limit of its working stroke, as hereinafter more fully explained.

The main lever just referred to is a three-armed lever whereof one arm 32 depends from the fulcrum of the lever and carries the roller 30 at its extremity, while the other arms 33 and 34, which are substantially horizontal, extend on opposite sides of the fulcrum; the arm 33 supporting a counter-weight 35 whereby the roller 30 is held in contact with the cam-bar 25, and the arm 34 serving to transmit motion to the valves as hereinafter explained. The fulcrum of the main lever is represented by a horizontal rocking-shaft 36 journaled in a bearing 37 (or bearings) on the stool 12, the arm 32 being fast on the inner end of the shaft while the arms 33 and 34, which extend in one plane, are fast on the outer end of the shaft beyond the stool 12.

In the example illustrated, the supply and exhaust of steam to and from the steam cylinder of the intensifier are controlled by double-beat drop-valves, and the supply and exhaust of steam to and from the lifting cylinders of the press are controlled by a single piston-valve, all these valves being mounted with the axes of their spindles extending vertically in the plane wherein the arms 33 and 34 of the main lever oscillate.

38 is the main steam pipe serving to lead steam to the steam inlet valve 39 of the intensifier and also to the piston-valve 40 for controlling the supply and exhaust of steam to the lifting cylinders of the press; the pipe 38 being connected to the body 41 of the valve 39 above the latter, while a passage 42 leads from the valve-body 41, at a point below the seat of the valve 39, to the lower end of the steam cylinder 11 of the intensifier. A passage 43 leads from the valve-body 41, at a point above the seat of the valve 39, to the inlet ports in the body 44 of the piston valve 40; the pipe which leads from this latter valve to the lifting cylinders of the press being connected to the valve-body 44 at 45.

46 is the steam exhaust valve of the intensifier, the body 47 of which communicates both with the passage 42 by way of a passage 48 above the seat of the valve 46, and also directly with the lower end of the steam cylinder 11 by way of a passage 48^a. The valve-body 47 communicates with the main exhaust pipe 49 by way of a passage 50 below the seat of the valve 46. The exhaust pipe 51 from the piston valve 40 leads into the passage 50; and in order to prevent the formation of an air cushion above the ascending steam piston of the intensifier, a pipe 52 maintains open connection between the upper end of the steam cylinder 11 and the exhaust pipe 49.

The spindle 53 of the steam valve 39 (which is loaded by a weight 54), and the

spindle 55 of the exhaust valve 46, are respectively coupled by pin-and-slot connections 56 and 57 to the opposite ends of a substantially horizontal lever 58 which is mounted to rock about a stationary fulcrum 59; while a link 60, attached to the lever 58 between the fulcrum 59 and point 57, serves to couple said lever to an intermediate point in the length of a floating lever 61 which extends in a substantially horizontal direction above the lever 58. One end of the floating lever 61 is connected with the arm 34 of the main lever through the medium of a lever 62 mounted to rock about a stationary fulcrum 63; one arm of this lever 62 being coupled to the arm 34 by means of an adjustable link 64 while the other arm of the lever 62 is connected with the adjacent end of the floating lever 61 by means of a link 65 which extends in alignment with the exhaust valve spindle 55 and is connected thereto by a pin-and-slot 66. The other end of the floating lever 61 is connected with the handing-lever 67 through the medium of a substantially horizontal lever 68 mounted to rock about a stationary fulcrum 69; one arm of this lever 68 being directly connected to the adjacent end of the floating lever 61 while the extremity of the other or long arm is coupled by an adjustable link 70 to an arm 71 fast on the shaft 72 of the handing lever.

At an intermediate point in its length, the long arm of the lever 68 has attached to it a vertical rod 73 which, depending in axial alignment with the stem 74 of the piston valve 40, is detachably coupled thereto by trip mechanism. This mechanism comprises an upright socket 75 pivoted at 76 to the valve stem 74 and serving as a guide for the rod 73 which is formed with a lateral notch 77 (Fig. 6); and a latch-bolt 78 which tends under the pressure of a spring 79 to engage the notch, but is controlled by means of a bell-crank lever 80 pivoted at 81 to the socket 75, this lever 80 being connected by a slotted link 82 with a stationary abutment-pin 83. The arrangement is such that when, during the working of the press with long strokes, the handing-lever 67 (which is shown as resting in normal position) has been moved a certain distance toward the right-hand in Figs. 1 and 5, so as to depress the long arm of the lever 68 to the full extent, the consequent descent of said arm will bring the notch 77 of the rod 73 into position to become engaged by the latch-bolt 78. Hence, when the handing-lever is afterward moved toward the left, the consequent ascent of the long arm of the lever 68 will raise the piston valve 40 along with the rod 73 until the exhaust port 84 of said valve is open to the exhaust pipe 51, 49. Just before the handing-lever reaches a certain intermediate position, the slotted link 82 will

be arrested by the pin 83 so as to cause the bell-crank lever to withdraw the latch-bolt 78 from the notch 77, whereupon the piston-valve 40, which is loaded by a dependent weight 85, will drop back to the normal position shown, wherein its steam-inlet port 86 is open to the passage 43 and main steam pipe 38; in which position the valve 40 remains throughout the rest of the throw of the handing-lever 67 toward the left, and thus maintains a cushion of live steam beneath the pistons of the lifting cylinders of the press so long as steam is admitted to the main steam pipe 38.

The type of hydraulic "working-valve" 22 which is illustrated in the drawings is a compound or pilot-controlled valve, and is seen in section in Fig. 7, wherein the pipe connections 21 and 24 are shown as extending at right angles to the direction in which they extend in Figs. 1 and 5. The valve-body 22 has a central chamber 87 into which the pipes 21 and 24 open from opposite sides, these pipes respectively leading, as already stated, from the hydraulic cylinder 14 of the intensifier, and underground to the main hydraulic cylinder of the press, while the pipe 23, leading underground to the air-vessel, opens from the bottom of the chamber 87. The main working-valve itself consists of a substantially cylindrical plug 88 which normally rests, as shown at 89, on a mitered seating around the mouth of the pipe 23; the plug 88 being of less diameter than the chamber 87 so as to leave the communication between the pipes 21 and 24 constantly open. The plug 88 has a central chamber 99 into which lateral ports 90 lead so as to enable communication to be established between the pipes 21 and 24 and a passage 91 which leads downward through the plug 88; this passage 91 being normally closed by a pilot-valve 92 which is slidably vertically through the plug 88 and which normally rests, as shown at 93, on a mitered seating around the mouth of the passage 91.

The plug 88 is not mechanically connected to any operating part, and lifts only when, owing to the main press-head and the intensifier ram descending by gravity, the pressure within the pipes 21, 24 becomes less than that within the air vessel and pipe 23; the function of the plug being to then open automatically and permit the pipes 21, 24 to become promptly filled with water from the air vessel. A spring 94 is coiled in compression about the stem 95 of the pilot-valve 92 between a nut 96 on the stem and a stationary bridge 97 secured to the valve-body 22 by pillars 98; the function of this spring 94 being to cause the pilot-valve 92 to close when permitted to do so, against the hydraulic pressure acting upon the full area of its lower end as compared with the pressure upon its upper end less the area of the

valve-stem 95. The pressure within the space 100 above the plug 88 and pilot-valve 92 is maintained constantly equal to that within the pipes 21, 24 by means of a duct 5 or ducts 101 leading into said space from the chamber 87. The pilot-valve 92 is raised against the stress of the spring 94 by means of a lever 102 the bifurcated end of which engages beneath the nut 96; this lever, which is mounted to rock about a stationary fulcrum 103, being coupled by an adjustable rod 104 with pin-and-slot connection to a short arm 105 fast on the shaft 72 of the handing-lever 67.

15 The improved apparatus as a whole is worked in substantially the same manner as the similar apparatus employed in connection with a non-inverted intensifier and will therefore be explained hereinafter in more 20 general terms. It will be understood that during resting conditions (*i. e.* with the handing-lever 67 standing in the mid position shown, the steam valve 39 and exhaust valve 46 of the intensifier both closed, the 25 piston valve open to admit steam beneath the pistons in the lifting cylinders of the press, the working-valve 88, 92 closed, the hydraulic ram 15 of the intensifier at the bottom of its travel, and the tool of the 30 press resting on its anvil), the press-head will not be raised although steam be admitted beneath the pistons of the lifting cylinders, for the reason that the hydraulic main pressure pipes 21 and 24, as well as 35 the hydraulic cylinder 14 of the intensifier and the main hydraulic cylinder of the press, are all filled with water.

If, now, it be desired to set the press in 40 operation, the water in the hydraulic main pressure pipes 21 and 24 must first be afforded freedom to escape so as to enable the steam pistons of the lifting cylinders to raise the main ram of the press sufficiently to accommodate the work on the anvil. This 45 is effected by opening the pilot-valve 92; for which purpose the handing-lever 67 must be moved toward the right in Figs. 1 and 5 so far as to cause the bifurcated lever 102 to open the pilot-valve 92 and thus afford freedom for the water in the pipes 21 and 24 to escape to the air-vessel by way of the passage 91 and pipe 23 as the main ram rises under the pressure of the steam in the lifting cylinders. While this is taking 50 place, the plug 88 of the working-valve remains seated owing to the rise of the main ram producing in the pipes 21, 24 a pressure higher than that in the air vessel and pipe 23. When the main ram of the press 55 has been raised sufficiently, the return of the handing-lever 67 to its mid or neutral position will allow the valve 92 to close and cut off communication between the air-vessel and the pipes 21 and 24.

60 65 The nature of the subsequent movements

of the handing-lever 67 will depend upon whether it is desired to work the press with long and comparatively slow strokes, or with short and rapid strokes. If short, quick strokes are required, the piston valve 40 70 must remain open to steam, so as to maintain a cushion of live steam beneath the pistons of the lifting cylinders; and for this purpose the oscillations manually imparted to the handing-lever must be kept within 75 the limits of that arc of its throw wherein the rod 73 fails to descend so far as to bring about the engagement of the latch-bolt 78 with the notch 77 and the consequent opening of the valve 40 to exhaust as the 80 rod 73 rises. With this proviso, the movements given to the handing-lever 67 in rapid working with short strokes are substantially the same as those imparted to it in working with long strokes, except in the following 85 respects.

That is to say, when it is desired to work the press with long and relatively slow strokes, it is necessary to open the lifting cylinders to exhaust at the beginning and 90 during the earlier part of the working stroke of the press, so as to allow the press-head to drop and prevent its again rising before the pressing stroke commences. For this purpose, at the commencement of each 95 long pressing stroke, the handing-lever 67 must be moved over to, or near, the right hand limit of its throw so as to insure that on its return movement toward the left the rod 73 in rising will open the valve 40 to 100 exhaust until the latch-bolt 78 becomes disengaged from the notch 77, which happens at about that angular position of the handing-lever whereat the steam valve 39 of the intensifier is opened. The dropping of the 105 valve 40 at about this moment insures the provision of a cushion of live steam beneath the pistons of the lifting cylinders in time to cause the press-head to rise promptly at the termination of the long pressing 110 stroke.

It will be observed that the steam and exhaust valves 39 and 46 are respectively opened, according as the handing-lever 67 is moved toward the left or the right of the 115 mid or neutral position wherein it is shown in Figs. 1 and 5; the long arm of the lever 68 being raised or depressed to a corresponding extent. According as said arm is raised or depressed, the floating lever 61 is depressed or raised about its point of attachment to the link 65, and through the link 60, rocks the lever 58 so as to open the steam valve 39 or the exhaust valve 46; the provision of the pin-and-slot connections at 56 and 57 insuring that the opening or closing of either valve will not necessarily affect the position of the other.

When the handing-lever is moved to and held in a position toward the left of its neu- 130

tral position so as to open the steam valve 39 to any desired extent, the consequent ascent of the hydraulic ram 15 will carry up with the latter the cam-bar 25, which 5 will force toward the left the arm 32 of the main lever and, by depressing the link 64, will raise the link 65 and impart to the floating lever 61 an upward angular movement about its point of attachment to the lever 68, 10 which is meanwhile held stationary by the handing-lever. The pin-and-slot attachment at 66 prevents the rise of the link 65 from lifting the spindle 55 and opening the exhaust valve 46; but the upward movement of the 15 floating lever 61 raises the link 60 and causes such angular movement of the lever 58 about its fulcrum 59 as to permit the steam valve 39 to close under the load of its weight 54, which happens at the moment 20 when the steam piston of the intensifier, and therefore also the ram 15 and cam-bar 25, have reached a point in their upward stroke corresponding to the angular position in which the handing-lever 67 is held.

25 When the steam piston closely approaches the upper limit of its working stroke, the roller 30 is engaged by the steep portion 31^a of the inclined operative edge 31 of the cam-bar 25, so that not only is steam cut off by 30 the closure of the steam valve 39, but at the same time the exhaust valve 46 is quickly opened to relieve the pressure beneath the steam piston and thus assist in the arrest of the latter before it can come in contact with 35 the top cover of the cylinder 11.

The whole of the above leverage-system, with the exception of that arm 32 of the counterweighted main lever which bears against the cam-bar 25, preferably extends 40 and moves in one plane as shown, so as, by obviating any tendency of the levers to cant laterally, to enable the use of way-shafts with duplex levers (involving the fitting of keys) to be dispensed with. Hence the ful- 45 crum-pins of the valve lever 58 and intermediate levers 62 and 68 can be made fixtures in a single bracket 106 bolted to the stool 12 which supports the steam cylinder 11, whereby accuracy of adjustment is fa- 50 cilitated; while the elimination of the movable control-bar, formerly used, reduces the liability to defective action consequent on vibrations set up in the valve-gear; any tendency to side thrust on the moving parts, 55 due to resistances in the mechanism, being obviated, and the action of the entire valve-gear being rendered smoother, more positive, and more direct than in mechanism of the same general type as heretofore used.

60 Owing to the relative arrangement of the parts in the "improved inverted" type of intensifier to which the present invention relates, the hydraulic working-valve can be placed at or near the ground-level and close 65 to the handing-lever as in the example illus-

trated, so as to be capable of actuation from the handing-lever through the medium of a horizontal shaft on which said lever is fast, and relatively short and compact lever-and-link connections adapted to afford the necessary lost motion. 70

Having now particularly described and ascertained the nature of my said invention and in what manner the same is to be performed, I declare that what I claim is:— 75

1. In a steam hydraulic intensifier of the kind referred to, the combination of a steam cylinder, a hydraulic ram, and mechanism for effecting control of the admission of steam to the steam cylinder jointly by a handing lever and by hunting gear, comprising a cam bar fixed to the movable ram member and having an inclined edge, a lever adapted to bear constantly against said inclined edge of the cam bar, and a floating 80 lever so coupled to said first-mentioned lever and to the valve of the steam cylinder that the point in the stroke of the steam piston whereat the supply of steam is cut off will be determined by the angular position of the 85 handing lever. 90

2. In a steam hydraulic intensifier of the kind referred to, the combination of a steam cylinder, a hydraulic ram, and mechanism for effecting control of the admission of steam to the steam cylinder jointly by a handing lever and by hunting gear, comprising a cam bar fixed to the movable ram member and having an inclined edge, a lever adapted to bear constantly against said inclined edge of the cam bar, and a floating lever so coupled to said first-mentioned lever and to the valve of the steam cylinder that the point in the stroke of the steam piston whereat the supply of steam is cut off will 100 be determined by the angular position of the handing lever. 105

3. In a steam hydraulic intensifier of the kind referred to, the combination of a steam cylinder, a hydraulic ram, and mechanism 110 for effecting control of the admission of steam to and from the steam cylinder jointly by a handing lever and by hunting gear, comprising a cam bar fixed to the movable ram member and having an inclined edge, a counterweighted lever adapted to bear constantly against said inclined edge of the cam bar, and a floating lever so coupled to said counterweighted lever and to the valve of the steam cylinder that the point in the 115 stroke of the steam piston whereat the supply of steam is cut off will be determined by the angular position of the handing lever. 120

4. In steam hydraulic intensifier of the kind referred to, the combination of a steam cylinder, a hydraulic ram, and mechanism for effecting control of the admission and exhaust of steam to and from the steam cylinder jointly by a handing lever and by hunting gear, comprising a cam bar fixed to 125 130

the movable ram member of the hydraulic portion of the intensifier and having an inclined edge, a lever adapted to bear constantly against said inclined edge of the cam bar and a floating lever so coupled to the handing lever and to said first-mentioned lever and to the valves of the steam cylinder that the point in the stroke of the steam piston whereat the supply of steam is cut off and the exhaust valve opened will be determined by the angular position of the handing lever.

5. In a steam hydraulic intensifier of the kind referred to, the combination of a steam cylinder, a hydraulic ram, and mechanism for effecting control of the admission of steam to the cylinder of the intensifier, a cam bar fixed to the movable ram member of the hydraulic portion of the intensifier and having an inclined edge, a lever adapted to bear constantly against said inclined edge of said cam bar, a handing lever and a floating lever coupled to said first-mentioned lever and to the valves of the steam cylinder, a valve controlling the lifting cylinders of the press, and a trip mechanism between the hand lever and said valve controlling the lifting cylinders.

6. In a steam hydraulic intensifier of the kind referred to, the combination with a steam cylinder and a hydraulic ram, of mechanism for effecting the control of the admission and exhaust of steam to and from the steam cylinder comprising a handing lever and a floating lever, connections between same, a cam bar fixed to the movable ram member of the hydraulic ram, and having an inclined edge, a lever adapted to bear

constantly against said inclined edge of the cam bar, a valve controlling the lifting cylinder of the press, and trip mechanism connected to said valve and coupled to the connection between the handing lever and the floating lever.

7. In a valve controlling mechanism for a steam hydraulic intensifier, the combination of a steam cylinder, a hydraulic ram, a cam bar fixed to the movable member of the hydraulic ram and having an inclined edge, a lever adapted to bear constantly against said inclined edge, a steam valve and connections between the same and said lever, the terminal portion of the inclined edge of said cam bar having a steeper slope than the main portion thereof, so as to be adapted to cause the exhaust valve of the steam cylinder to open rapidly as the steam piston closely approaches the upper limit of its working stroke.

8. In valve controlling mechanism for the steam hydraulic intensifier, the combination of a steam cylinder, a hydraulic ram, a cam bar fixed to said movable member of said hydraulic ram and having an inclined edge, a valve of the steam cylinder, and a lever adapted to bear constantly against the inclined edge of the cam bar and connected to said valve, the terminal portion of the inclined edge of the cam bar having a steeper slope so as to be adapted to cause the exhaust valve of the steam cylinder to open rapidly as the steam piston closely approaches the upper limit of its working stroke.

THOMAS WILTON HAND.
